United States Patent Office

Des. 202,221
Patented Sept. 7, 1965

202,221

DECANTER AND CLOSURE THEREFOR

Ernest L. Du Pree, New York, N.Y., assignor to Schenley
Industries, Inc., New York, N.Y., a corporation of
Delaware

Filed July 14, 1964, Ser. No. 80,862

Term of patent 14 years

(Cl. D58—6)

FIG 1

FIG 2

FIG 5

FIG.3

FIG 4

FIG 6

FIG 7

FIG 8

FIGURE 1 is a front elevational view of a decanter and closure therefor embodying my new design;

FIGURE 2 is a side elevational view thereof, taken from the right side of FIGURE 1, and showing the decanter with the closure removed;

FIGURE 3 is a top plan view of the decanter and closure of FIGURE 1;

FIGURE 4 is a top plan view of the decanter of FIGURE 2;

FIGURE 5 is a sectional view taken on the line 5—5 of FIGURE 3;

FIGURE 6 is a fragmentary sectional view taken on the line 6—6 of FIGURE 4;

FIGURE 7 is a fragmentary sectional view on the line 7—7 of FIGURE 2;

FIGURE 8 is a rear elevational view of the decanter and closure shown in FIGURE 1; and

FIGURE 9 is a side elevational view thereof, taken on the line 1—1 of FIGURE 1, and showing the decanter with

FIG 9

I claim:

The ornamental design for a decanter and closure therefor, as shown.
